UNITED STATES PATENT OFFICE.

THOMAS B. GREENLAW, OF FLORA, ILLINOIS.

FOUNTAIN-PEN HOLDER.

1,413,476.

Specification of Letters Patent. Patented Apr. 18, 1922.

Application filed February 14, 1921. Serial No. 444,916.

To all whom it may concern:

Be it known that I, THOMAS B. GREENLAW, a citizen of the United States, residing at Flora, in the county of Clay and State of Illinois, have invented certain new and useful Improvements in Fountain-Pen Holders; and I do declare the following to be a full, clear, and exact description of the invention, such as will enable others skilled in the art to which it appertains to make and use the same.

This invention relates to improvements in fountain pen-holders and has for its principal object the provision of a simply constructed device of this character which will readily flow any quality of writing ink.

Another object is to provide a device of this character wherein a maximum quantity of ink may be retained and fed to a pen without blotting the surface of the writing paper.

With these and numerous other objects in view, my invention resides in the novel features of construction, and in the combination and arrangement of the several parts as illustrated in the accompanying drawings and more particularly pointed out in the specification and claims.

In the accompanying drawings:—

Figure 1 is a side elevation of my invention, the pen stock or barrel being shown in section;

Fig. 2 is top plan view thereof;

Fig. 3 is a bottom plan view thereof;

Fig. 4 is a central vertical longitudinal section on the line 4—4 of Fig. 2;

Fig. 5 is a transverse section on the line 5—5 of Fig. 4;

Fig. 6 is a plan view of the blank from which my improved pen is formed;

Fig. 7 is a side elevation of a modified form of my invention;

Fig. 8 is a top plan view thereof;

Fig. 9 is a central vertical longitudinal section on the line 7—7 of Fig. 8;

Fig. 10 is a plan view of the blank from which this form is made;

Fig. 11 is a side elevation with parts in section of a further modification of my invention;

Fig. 12 is a top plan view thereof;

Fig. 13 is a central vertical section thereof;

Fig. 14 is a transverse section on the line 14—14 of Fig. 13;

Fig. 15 is a transverse section on the line 15—15 of Fig. 13; and

Fig. 16 is a plan view of the blank from which this form is made.

Similar numerals of reference are employed to indicate corresponding parts throughout the several views.

The preferred embodiment of my invention as clearly illustrated in Figs. 1 to 6 of the drawings, comprises a penstock 1 provided at one end with a longitudinal socket 2 in which is adapted to be disposed a double-ended reversible ink reservoir and pen holder 3 which is formed from a single sheet of suitable metal. In forming said ink reservoir an elongated piece of sheet metal is bent upon itself to form a substantially trough or U-shaped body having parallel spaced walls 4, which are provided with a plurality of preferably transversely aligned apertures 5 adapted to assist in retaining ink in the trough-shaped body. The upper edges of the opposite longitudinal walls 4 are bent outwardly and downwardly adjacent said walls to form flanges 6 adapted to increase the ink retaining surface of the reservoir, said flanges being provided with a plurality of apertures 7 substantially transversely aligned with the apertures 5 in the U-shaped portion and for a similar purpose.

The reservoir is provided at each end with a substantially semi-cone-shaped feed portion 8 having an open top and a small outlet opening 9 in its extreme end, said outlet being positioned adjacent the feed opening of a pen 10 whose inner end is releasably retained between the downwardly bent flanges 6 and the flanges 11 which are curved upwardly and inwardly from the lower edges of the aforesaid flanges 6 which extend longitudinally of said body. The lines of fold in forming the reservoir are indicated by dotted lines in Fig. 6 of the drawings.

In operation, the ink will be retained in the reservoir between the several walls and flanges and ink will be fed through the semi-cone-shaped feed portions at the ends of said reservoir and received in the feed opening in the pen from which it will pass to the points of the pen.

In a modified form illustrated in Figs. 7 to 10 inclusive, the penstock 1' is formed integral with the ink reservoir which comprises an elongated strip of sheet metal bent upon itself to form a substantially trough or U-shaped body having parallel spaced walls 4' provided with a plurality of pref-

erably transversely alined apertures 5' adapted to assist in retaining the ink in said body. The upper edges of the walls 4' are bent outwardly and downwardly adjacent 5 said walls to form flanges 6', said flanges being provided with a plurality of apertures substantially transversely alined with the apertures 5' and for a similar purpose.

The reservoir is provided at its outer end 10 with a substantially semi-cone-shaped feed portion 8' having open top and a small outlet opening 9' in its extreme end, said outlets being positioned adjacent the feed opening of a pen 10' whose inner end is releasably retained between the flanges 6' and the flanges 11' which are curved upwardly from the flanges 6'.

The penstock 1' is formed from a continuation of the other end of the reservoir. The 20 lines of fold in forming this reservoir are indicated by dotted lines in Fig. 10 of the drawings.

A second modified form of this invention is illustrated in Figs. 11 to 16 inclusive 25 which in this instance comprises a reservoir having a single feed portion 8" on one end and adapted to have its other end received in an ordinary fountain barrel 1" which is provided with a cap 13. In this form, the 30 reservoir is also formed from an elongated strip of sheet metal bent upon itself to form a substantially U-shaped body having parallel spaced walls 4" which are provided with a plurality of substantially transversely alined apertures 5" adapted to assist in retaining ink in the body.

The upper edges of the walls 4" are bent outwardly and downwardly to form longitudinal flanges 6" which are provided with 40 a plurality of apertures 7" substantially transversely alined with the other apertures 5" and for a similar purpose. The reservoir is of such a diameter as to tightly wedge the pen 10" between the inner wall of the barrel 1" and the point of juncture of the walls 4" and flanges 6" of said reservoir. In this 45 form the reservoir is provided with only one feed portion 8" which is disposed beneath the pen 10" in the same manner as the other forms.

Fig. 16 shows the blank from which the form is made and the dotted lines indicate the lines of fold.

From the foregoing description, taken in 55 connection with the accompanying drawings, the construction and operation of my improved fountain pen holder will be readily understood, but it is also to be understood that within the scope of the appended claims, numerous changes may be made without sacrificing the principal advantages.

I claim:

1. A fountain pen holder comprising a 65 penstock, a pen, a longitudinal ink reservoir

disposed beneath said pen, said reservoir comprising a body substantially U-shaped in cross section, the opposite side walls of said body being provided with a plurality of apertures, said walls having their upper longitudinal edges bent outwardly and downwardly upon themselves and spaced from said walls, and a semi-cone shaped feed portion on the outer end of said body terminating adjacent the feed opening in said pen. 70 75

2. A fountain pen holder comprising a penstock, a pen, a longitudinal ink reservoir disposed beneath said pen, said reservoir comprising a body substantially U-shaped in cross section, the opposite side walls of said body being provided with a plurality of apertures, said walls having their upper longitudinal edges bent outwardly and downwardly upon themselves and spaced from said walls, upwardly and inwardly curved longitudinal flanges formed on said downwardly bent edges and spaced therefrom for the reception of said pen therebetween, and a semi-cone shaped feed portion formed on 80 85 the outer end of said body and terminating adjacent the feed opening in said pen. 90

3. A fountain pen holder comprising a penstock, a pen, a longitudinal ink reservoir disposed beneath said pen, said reservoir comprising a body substantially U-shape in cross section, the opposite side walls of said body being provided with a plurality of apertures, the upper longitudinal edges of the side walls of said body being bent outwardly and downwardly upon themselves and spaced from said walls, said walls and downwardly bent portions being provided with a plurality of transversely alined apertures, upwardly and inwardly curved longitudinal flanges formed on said downwardly bent portions and spaced therefrom for the reception of said pen therebetween, and a semi-cone shaped feed portion formed on the outer end of said body and terminating adjacent the feed opening in said pen. 100 105 110

4. A fountain pen holder comprising a tubular pen stock, a reversible longitudinal ink reservoir disposed in said penstock, said reservoir comprising a body substantially U-shaped in cross section, integral semi-cone shaped feed portions formed on the opposite ends of said body, a pen disposed at one end of said body and having its feed opening positioned adjacent the outer terminal of the feed portion, and means for retaining the pen on said body. 115 120

5. A device of the class described comprising an elongated tubular penstock, a reversible longitudinal ink reservoir adapted to have one end received in said penstock, said reservoir comprising a body substantially U-shape in cross section, said body having the upper longitudinal edges of its side walls bent outwardly and downwardly 125 130 135

upon themselves and spaced from said walls to form flanges, upwardly and inwardly curved longitudinal flanges formed on the lower edges of the downwardly bent portions and spaced therefrom, said walls and flanges being provided with a plurality of transversely alined apertures adjacent one end, a pen disposed at one end of said body and received between said flanges, and an integral semi-cone shaped feed portion on

each end of said body adapted to terminate at the feed opening of a pen.

In testimony whereof I have hereunto set my hand in the presence of two subscribing witnesses.

THOMAS B. GREENLAW.
